RAILWAY TRAFFIC CONTROLLING SYSTEM

Sedgwick N. Wight, Rochester, N. Y., assignor to
General Railway Signal Company, Rochester,
N. Y.

Application July 31, 1934, Serial No. 737,780

5 Claims. (Cl. 246—3)

This invention relates to traffic controlling systems for railroads and it more particularly pertains to a system for the remote control of power-operated switch machines.

5 In a system of remote control of power-operated switch machines for use in connection with terminals, interlocking plants and centralized traffic controlling systems, it is desirable to obtain the various controls and indications required 10 for efficient operation of a switch machine over a minimum number of line wires between the tower or control office for each switch. Therefore one object of the present invention is to provide a simple and reliable arrangement of line circuits and relays so related that several 15 different distinctive controlling conditions may be transmitted or communicated instantaneous- 5
ly in response to the energization or deenergization of the line circuits.

20 More specifically, this invention provides for the transmission over a single polarized line circuit of the controls required for a power-operated switch machine and the provision in connection with the approach and detector locking usually 25 employed with power-operated switch machines, of an improved circuit arrangement for requiring the movement of the control lever at the time the approach and detector locking is not effective in order to operate the switch machine so 30 that such switch machine will not operate after a train movement over the switch until the operator shifts the control lever.

35 Various other characteristic features and advantages of the invention will be in part apparent and in part specifically pointed out as the description progresses.

In describing the invention in detail reference 40 will be made to the accompanying drawing, which is a diagrammatic illustration of one specific embodiment of the present invention as applied to the control of traffic over a single railroad track switch.

45 Although the traffic controlling system of the present invention may be applied to various track layouts involving conflicting and non-conflicting routes and various other conditions encountered in practice, it has been specifically illustrated as applied to a single track switch and preferably associated with an automatic block signal system 50 of the type for example as disclosed in my prior patent, No. 2,082,436 dated June 1, 1937. With reference to the accompanying drawing the railroad track switch TS is illustrated as connecting the rails 3 of a main track to the rails 4 of a di- 55 verging or turn-out track. This track switch TS

is operated by a power driven switch machine SM which may be of any suitable type, such for example as disclosed in the patent to W. K. Howe, No. 1,466,903, dated September 4, 1923. This switch machine may be provided with a dual control selector to permit hand operation of the track switch such as shown for example in the patent to W. K. Howe, No. 1,852,573 dated April 5, 1932.

5 The main track adjacent the track switch TS and a portion of the diverging track to the foul- 10 ing point comprises a detector track circuit of the closed circuit type with the usual track battery 5 and track relay T, which detector track circuit is insulated from the rest of the track 15 layout by the usual insulated joints.

Traffic over the track switch in an eastbound 20 direction is governed by signals 1 and 1D on the main track and on to the turn-out track respectively. Traffic over the track switch in a west- 25 bound direction is governed by signals 2 and 2D on the main track and off the turn-out track 30 respectively.

The track switch and the switch machine are 35 preferably provided with point detector contacts of some suitable type such for example as disclosed in the patent to C. S. Bushnell, 1,517,236, dated November 25, 1924. These point detector contacts are employed to energize a switch position repeating relay of the usual polar neutral 40 type in accordance with the position and locked or unlocked condition of the track switch but since this particular feature forms no part of the present invention it has been omitted from the drawing for the sake of simplicity.

A polar neutral relay WZ preferably of the magnetic stick type is governed from the control office over a suitable polarized line circuit including line conductor 6. The polar contact 7 of the relay, when operated to one or the other of its extreme positions, serves to operate the switch machine to normal or reverse extreme locked positions. Since this portion of the operation of the system is immaterial for an understanding of the present invention it is only indicated by 45 dotted line 8 leading from contact 7 to the switch machine.

A time element device TE, a neutral stick relay S and a neutral lock relay L are associated with the track relay T and with relay M in such a 50 manner as to provide approach locking for track switch TS with suitable time release control, all of which has been more completely disclosed in the prior patent to R. M. Phinney, Patent No. 2,082,741, dated June 1, 1937. A neutral relay M 55

is energized whenever all signals are at stop and deenergized when any one of the signals is cleared.

In the control office a suitable control machine 5 is provided with the usual miniature track diagram having control levers and indicators advantageously located thereon. For convenience in describing the present invention only the switch machine control lever SML and signal 10 control lever SGL for governing track switch TS and the associated signals have been shown. Lever SML is preferably of the two-position quick acting type operating its contacts to either the extreme normal or reverse position. In other 15 words, contacts 9 and 10 of lever SML snap from one position to the other in response to the actuation of lever SML irrespective of whether this lever is quickly or slowly operated.

The control of the signals by lever SGL is 20 merely indicated by dotted line 16 since the detailed operation of such control is immaterial.

A lock repeating relay LP is provided in the control office, which relay is of the retained neutral polar type, that is, its polar contacts are 25 operated to the right when (+) potential is applied to the line circuit 6 from the control office battery and to the left when (−) potential is applied to this line circuit from the control office battery. The neutral contacts assume picked up 30 positions when the winding of this relay is energized and the operation distinguishes from the usual neutral polar type relay in that the contacts are not dropped when the current is suddenly reversed in the winding of the relay. This is indicated by the shaded portion of the relay on 35 the drawing. Such operation of the LP relay may be obtained in any approved manner, one such type of relay being disclosed in the patent to F. C. Larson, No. 1,852,210, issued April 5, 1932.

To simplify the illustrations the circuits are 40 illustrated in a conventional manner with the symbol (+) indicating the positive terminal and the symbol (−) indicating the negative terminal of a suitable battery or other source of current, 45 with the circuits to which these terminals are connected having current flowing from (+) to (−). Symbol (B+) is associated with the (+) terminal and symbol (B−) is associated with the (−) terminal of suitable batteries or other 50 sources of current located in the control office and at the field station, each having a mid-tap (CN). In this connection it is to be understood that the terminal (CN) at the field station is connected to the mid-tap of the control office battery over a common return conductor which 55 is not shown.

In accordance with the present invention it is contemplated that the track adjacent to the track switch TS will in practice be provided with track 60 circuits, wayside signals, line circuits and the like, constituting suitable approach locking for the switch. The specific details of such approach locking circuits are immaterial to the present invention and therefore have been omitted.

Lock indicator lamp LI is provided to give the operator an indication when the switch at the 65 associated field station is in its locked condition. This lamp serves as an indication to the operator not to move the switch machine lever to a new position when it is lighted. In the event that the lever is moved to a new position when the lamp is lighted then the "electric lock equivalent" 70 feature is effective to prevent any response to 75 such lever actuation at the field station until the

lever is returned to its former position and then actuated when the switch is unlocked.

Contacts 11, 12 and 13 are associated with signals 1, 2 and 2D respectively and are included in a series circuit leading to relay M for the 5 purpose of maintaining relay M in its picked up condition as long as all signals are at stop and for dropping relay M when any signal is cleared, which results in opening its associated contact.

It will be understood that other details and 10 adaptations may be incorporated in the present system when desired. For example, in order to provide steady energization for the completion of the stroke of the switch machine or in other words "electrical bias control", a lock stick relay 15 may be provided.

It is believed that further description of the present invention will best set forth the characteristic features and functions of the system by 20 considering the operation under certain characteristic or typical conditions.

OPERATION

Normal conditions.—With the detector track section unoccupied and with the switch control 25 section SML in the position shown, the various devices, relays and circuits assume positions and conditions of energization as illustrated. Since it is assumed that the illustrated track section is unoccupied track relay T is normally energized. 30

Since all signals are at stop a circuit is completed for energizing relay M which extends from (+), contact 11 of signal 1 in its stop position, contact 12 of signal 2 in its stop position, contact 13 of signal 2D in its stop position and winding 35 of relay M, to (−).

Relay S is normally energized over a circuit extending from (+), through the operating element 40 14 of the timing device TE, front contact 15 of relay S, winding of relay S and front contact 18 of relay M, to (−). It will be understood that the resistance of relay S is sufficiently high to prevent the operation of the time element device over the circuit just described.

With relays T and S energized and with the 45 time element device in its normal condition, an energizing circuit is closed for relay L extending from (+), contact 19 of time element device TE, front contact 20 of relay S, winding of relay L and front contact 21 of relay T, to (−).

The normal energizing circuit for relay WZ extends from (B+) in the control office, contact 10 50 of lever SML in its normal position, front contact 22 and polar contact 23 in multiple of relay LP, winding of relay LP, line conductor 6, front contact 24 of relay L, winding of relay WZ to terminal CN and thence over the common conductor (not shown) to the control office and to the mid-tap of the control battery. This energization of 55 relays LP and WZ causes their polar contacts to be actuated to the right and the neutral contacts of relay LP to be picked up, all as indicated in the drawing.

Manual control of the track switch.—It will now be assumed that the operator moves the 60 switch machine control lever SML to its reverse dotted line position. As above mentioned contacts 9 and 10 are preferably of the snap action type so that the current through the winding of relay LP (which relay is slightly slow acting) is 65 quickly reversed so that relay LP does not drop its neutral contacts. As also above mentioned this relay is of the retained neutral polar type so that the sudden reversal of current in its winding does not kick down its neutral contacts. 75

The reversal of current effected by the actuation of lever SML to its reverse position is due to a circuit extending from (B-), contact 9 in its dotted line position, front contact 25 of relay LP, 5 winding of relay LP, line conductor 6, front contact 24 of relay L and winding of relay WZ, to CN.

Polar contact 7 of relay WZ is actuated to its left hand dotted position which energizes a circuit effective to operate the switch machine for placing the track switch in its reverse position.

The response of the track switch may be indicated to the operator by the energization of suitable indicators from the contacts of the switch 15 repeating relay (not shown), which relay may be provided with polar and neutral contacts to accomplish such indication, all in accordance with practices heretofore disclosed but not shown in the present disclosure because such operation is 20 immaterial to an understanding of the present invention.

The operation involved in actuating the track switch from its reverse locked position to its normal locked position is merely the inverse of that 25 already described and need not be specifically pointed out. It need only be mentioned that the return of lever SML to its normal position reverses the current flow through relay WZ for positioning contact 7 back to its right hand position 30 which, through the medium of switch machine SM, actuates the track switch to its normal position. During this operation the reversal of current through the winding of relay LP takes place in such rapid order that its neutral contact 22 35 is not dropped so that its energizing circuit is established even before contact 23 is actuated back to its right-hand position.

Manual control of signals.—Assuming clear traffic conditions, either signal 1 or 2 may be 40 cleared with the track switch in a normal position and either signal 1D or 2D may be cleared with the track switch in a reverse position. The signals are governed in accordance with the position of signal lever SGL. When actuated to the 45 right or to the left the operator is able to establish traffic in either east or west-bound directions. As above mentioned the detailed circuits for clearing these signals is not shown but it will be understood that the series circuit including relay M is opened when any signal is 50 cleared due to the opening of some one of the contacts 11, 12 or 13.

The deenergization of relay M in response to 55 clearing a signal opens the stick circuit of relay S at front contact 18 of relay M. This causes relay S to drop its contacts which in turn deenergizes relay L at front contact 20. The dropping of contact 24 of relay L prevents the operator from reversing the polarity to the winding 60 of relay WZ during any time that a signal governing traffic over the track switch is clear. The dropping of contact 24 deenergizes line conductor 6 which drops the neutral contacts of relay LP. A circuit is now closed at back contact 26 of 65 relay LP for lighting lamp LI as an indication that the track switch is locked.

During the deenergization of conductor 6, local energy is applied to the winding of relay WZ, the 70 polarity of which corresponds to the last polarity which actuated relay WZ over conductor 6. This holds the contacts of the WZ relay in their last operated positions during the time that its remote control circuit is opened at relay L. In this case for example, relay WZ is energized over a 75 circuit extending from (B+), contact 27 of relay

WZ in its right-hand position, back contact 24 of relay L and winding of relay WZ, to CN.

Since relay LP in the control office is deenergized, the movement of lever SML will neither effect the operation of relay WZ or relay LP. 5 This provides the "electric lock equivalent" feature which will be later described.

Approach locking and time release.—As the operator anticipates the approach of a train and sets up a particular route by clearing a signal for 10 that route (as above explained for example) and then attempts to alter the route already established, he is prevented from operating the track switch for a predetermined time after the signals governing that route have been returned to their 15 stop conditions. This predetermined time is measured by the time element device TE, which includes both the heating and cooling time of its thermal element as more specifically pointed out in the above mentioned prior patent, Patent 20 No. 2,082,741.

For example, it will be assumed that the operator returns signal 1 to stop which results in the energization of relay M over the previously described circuit. Relay M closes a circuit extending from (+) through the heating element of the device TE, back contact 15 of relay S and front contact 18 of relay M to (-). Sufficient current flows through this circuit to cause the heating element 14 to actuate contact 19 to its 30 open position and to actuate contact 29 to its closed position. The opening of contact 19 maintains relay L deenergized which keeps the switch locked. The closure of contact 29 completes a pick-up circuit for relay S which extends from 35 (+), contact 29, winding of relay S and front contact 18 of relay M, to (-). Relay S is then stuck up over its previously described stick circuit, which circuit now includes contact 29 in shunt of heating element 14. This shunting or short 40 circuiting of element 14 allows the time element device to cool sufficiently to again close contact 19 and to open contact 29. Closed contact 19 completes the pick-up circuit for relay L and open contact 29 removes the shunt from element 45 14 so that the circuits are in their normal condition as previously described.

Thus the operator may change a route only after a predetermined time in the face of an on-coming train, which allows the train sufficient 50 time to either stop before it reaches the track switch or to enter the detector track section and thereby prevent the operation of the switch machine.

Electric lock equivalent.—The electric lock 55 equivalent feature is effective in the event that the operator actuates lever SML to a new position while the track switch is locked as indicated by relay L being deenergized. With the circuits in the conditions indicated, it will be 60 assumed that relay L is dropped to lock track switch TS and that the operator actuates lever SML to its dotted line position before relay L is picked up. This has no effect on relay LP (which is deenergized by the dropping of relay 65 L) nor relay WZ when relay L is again picked up because the circuit from (B-) through contact 9 in its dotted line position is open at front contact 25 of relay LP and since contact 28 of relay LP was left in its right-hand position the 70 circuit is likewise open at this point.

It is therefore necessary for the operator to restore lever SML to its full line position which closes a circuit from (B+) contact 10 of lever SML, contact 23 of relay LP in its right-hand 75

position, winding of relay LP, over line conductor 6 and through the winding of relay WZ to the mid-tap of the control office battery. This picks up the neutral contacts of relay LP, after which 5 lever SML may be actuated to its dotted line position for closing a circuit from (B-), through contact 9 of lever SML, front contact 25 of relay LP and over the previously described circuit for controlling relay WZ.

10 For the reverse condition, relay LP will have its neutral contacts positioned to the left with lever SML in its dotted line position. Then when the switch is locked the dropping of relay L deenergizes relay LP for dropping its neutral contacts. If lever SML is then moved to its 15 full line position, relay LP cannot be picked up as long as front contact 24 of relay L is open. It cannot be picked up when this contact again closes, from (B+) through contact 10 of lever 20 SML, because polar contact 23 of relay LP is in its dotted line position and neutral contact 22 is dropped. By restoring lever SML to its dotted line position for picking up relay LP (after the switch is unlocked) over a circuit extending from 25 (B-), contact 9 of lever SML in its dotted position and contact 28 of relay LP in its left-hand dotted position, then lever SML will be effective to energize the control line circuit from (B+), contact 10 of lever SML and front contact 22 30 of relay LP over the previously described circuit.

It will thus be observed that relay LP is an indicating means for indicating (by means of back contact 26) the locked and unlocked condition of the remote track switch. Furthermore, 35 this LP relay registers (by means of its contacts 23 and 28) the particular control which is effectively applied to the control line circuit by the lever. These contacts maintain the circuit to the control line opened when relay LP has dropped its neutral contacts in response to 40 a locked condition of the switch control means, whenever the control lever is out of correspondence with contact 23 or 28 of this relay.

45 It is to be understood that the principles of the invention may be applied to various other types of systems and that various types of track layout may be controlled in a similar manner without departing from the spirit of the present invention, the track layout of the present disclosure being chosen merely for providing a simplified showing which could be clearly described in the specification.

Having described a traffic controlling system 55 as one specific embodiment of the present invention it is desired to be understood that this form is selected to facilitate in the disclosure rather than to limit the number of forms which it may assume and it is to be further understood that 60 various modifications, adaptations and alterations may be applied to the specific form shown in order to meet the requirements of practice without in any manner departing from the spirit or scope of the present invention except as limited by the appended claims.

Having described my invention what I claim is:—

1. In a centralized traffic controlling system for railroads, a track section, a track switch associated with said section, a control lever, a control circuit distinctively energized in accordance with the position of said lever, switch control means responsive to the actuation of said lever for controlling the operation of said track switch, 70 locking means responsive to specific conditions

of said section for locking and unlocking said switch control means, a polar neutral relay included in said control circuit, and means including contacts of said polar neutral relay and contacts of said control lever for preventing operation of 5 said switch control means subsequent to the restoration of said locking means to an unlocked condition if said control lever has been moved to a different position while said locking means was effective.

2. In a system for the remote control of power operated switches, a control circuit over which a power operated switch machine is controlled, a switch control relay and a neutral polar lock repeater relay connected in series in said control circuit, a lock relay, a control lever, means responsive to the actuation of said lever for actuating said switch control relay and said lock repeater relay to corresponding positions in accordance with the distinctive energization of said 20 control circuit, means controlled by said lock relay for preventing the actuation of said switch control relay, and means including cooperating contacts of said lock repeater relay and contacts of said lever for rendering said lever ineffective 25 to control the energization of said control circuit if said lever should be moved to a different position while said lock relay is effective to prevent the actuation of said switch control relay.

3. In a system for remote control of power 30 operated track switches, a manually operable lever at a control point, a control circuit extending from the control point to a distant track switch, switch control means adjacent the switch and responsive to the polarity of energization of 35 said control circuit for governing operation of said switch to a normal or a reverse position, locking means for at times opening said control circuit to prevent operation of said switch control means under traffic conditions adverse to 40 such operation, a neutral polar relay at said control point included in said control circuit, circuit means associated with said polar neutral relay and said lever for rendering the initial energization of said relay and the continuity of said control circuit dependent upon correspondence between the position of the polar contacts of said relay and the contacts of said lever after said control circuit has been opened and reclosed by 45 said locking means, and means associated with 50 said polar neutral relay and acting after such initial energization thereof to maintain the continuity of the control circuit independently of such correspondence and thereby permit a change in the energization of said control circuit by a subsequent movement of said lever.

4. In a system for remote control of power 55 operated track switches, a manually operable lever at a control point, a control circuit extending from the control point to a distant track 60 switch, switch control means adjacent the switch and responsive to the polarity of energization of said control circuit for governing operation of said switch to a normal or a reverse position, locking means for at times opening said control 65 circuit to prevent operation of said switch control means under traffic conditions adverse to such operation, a neutral polar relay at said control point included in said control circuit, contact means operated by the neutral armature 70 of said neutral polar relay for opening said control circuit, and circuit means including polar contacts of the neutral polar relay and contacts of the lever in corresponding positions for providing a shunt for said contact means, whereby 75

operation of the switch control means is prevented if said lever is moved to a different position while said locking means is effective to open said control circuit but is permitted if said lever is moved to a different position while said locking means is ineffective.

5. In a system for remote control of power operated track switches, a manually operable lever at a control point, a control circuit extending from the control point to a distant track switch, switch control means adjacent the switch and responsive to the polarity of energization of said control circuit for governing operation of said switch to a normal or a reverse position, locking means for at times opening said control circuit to prevent operation of said switch control means under traffic conditions adverse to such operation, a retained-neutral-polar relay at said control point included in said control circuit and responsive to current flow therein so as to pick up its neutral contacts when energized

and drop them when deenergized with its polar contacts operating to positions dependent upon the polarity of such energization, said retained-neutral-polar relay being so constructed as to maintain its neutral contacts picked up upon a relatively quick reversal of the polarity of its energization, contact means operated by the neutral armature of said retained-neutral-polar relay for opening said control circuit, and circuit means including polar contacts of the retained-neutral-polar relay and contacts of the lever in corresponding positions for providing a shunt for said contact means, whereby operation of the switch control means is prevented if said lever is moved to a different position while said locking means is effective to open said control circuit but is permitted if said lever is moved to a different position while said locking means is ineffective.
